UNITED STATES PATENT OFFICE.

SAMUEL M. LANGSTON, OF WENONAH, NEW JERSEY.

MACHINE FOR CUTTING COMPOSITION SHINGLES.

Application filed June 30, 1922. Serial No. 571,983.

To all whom it may concern:

Be it known that I, SAMUEL M. LANGSTON, a citizen of the United States, and resident of Wenonah, in the county of Gloucester and State of New Jersey, have invented certain new and useful Improvements in Machines for Cutting Composition Shingles, of which the following is a specification.

10 In the manufacture of shingle strips of the type having slots or recesses extending inwardly from one longitudinal edge to leave spaced tabs which in the finished roof simulate individual shingles, it is common practice to make the strips of a length equal to the width of a sheet from which the strips are cut, and to continuously deliver the sheet endwise through cutting mechanism which forms successive transverse rows 20 of longitudinally extending slots and transverse cuts intersecting these slots to subdivide one shingle strip from the next.

Various machines have been designed to cut strips in this general way, but all such machines with which I am familiar are open to some objection. If the slots are formed by a pair of coacting rotary members which cut all four sides of the slot at a single operation, some of the circumscribed pieces cut 30 out to form the slots or recesses may not be completely severed, due to dull knives or lack of proper adjustment, and may therefore remain in place, necessitating manually removing them from the completed strips. 35 The pieces, even though completely severed at all edges, may in being removed, fall on the surface of the sheet or the strips and become incorporated in the stack or bundle between superposed strips, thus marring or 40 indenting the latter. They may be completely removed by the cutting mechanism but become jammed in the latter so as to break the knives or require a stopping of the machine to loosen or remove them.

45 A common form of cutting mechanism on the market severs only three sides of the slot to leave tongues in place, and the fourth side of the slot, that is the base of the tongue, is severed by the main chopper which makes the transverse cuts between adjacent strips. This necessitates mechanism to knock out the waste pieces, but if they fall on the completed strips or hang by one edge, or corner where they are not

completely cut, they may get included in the bundle of strips and cause trouble.

One object of my invention is to insure the complete and positive removal of the waste pieces before the sheet reaches the chopper or other cut off mechanism, so that there is no liability of any of them being carried along and piled up in the stack of completed strips. A further object is to provide a simple and inexpensive means for severing and removing the tongues formed after first cutting three sides of the slot by any suitable cutting means. A further object is to provide a simple and improved mechanism for removing the waste piece which is positive in operation, and which directly coacts with means for cutting only one of the two opposite sides of the piece to be removed, so that there is no liability of the piece being jammed or held between parallel knives simultaneously cutting opposite edges of the slot.

Other objects and advantages will be pointed out hereinafter, or will be apparent from a consideration of the specific form illustrated in the accompanying drawings. In these drawings:

Fig. 1 is a longitudinal vertical section of the main operating parts of a machine shown diagrammatically.

Fig. 2 is a vertical transverse section substantially on the line 2—2 of Fig. 1, but on a larger scale.

Fig. 3 is a transverse section on the line 3—3 of Fig. 2.

Fig. 4 is a vertical transverse section on the line 4—4 of Fig. 1, but on the same scale as Figs. 2 and 3.

Fig. 5 is a transverse section on the line 5—5 of Fig. 4.

Fig. 6 is a section on the line 6—6 of Fig. 4, but on a larger scale.

Fig. 7 is a face view of a portion of the upper rotary member shown in Fig. 6.

Fig. 8 is a face view of a portion of the lower rotary member shown in Fig. 6.

Fig. 9 is a plan view of a sheet showing the successive steps in the operation of cutting it into strips, and

Fig. 10 is a view of a sheet as cut by a modification in the sizes and relative proportions of the parts of the cutting mechanism.

In the machine as diagrammatically illus-

trated in Fig. 1, the sheet is continuously fed through the machine at the proper speed, and by means of feed mechanism not illustrated. The sheet A passes between a pair of coacting members 10 and 11 which serve to form U-shaped cuts *a* defining tongues *b* each having one end remaining attached to the body of the sheet. These tongues are arranged in rows which extend transversely of the sheet, and the tongues in each row extend lengthwise of the sheet. Although either end of the tongue may be attached, it is preferably the forward or advancing end which is attached so that the tongue will be drawn along by the body of the sheet. The sheet then passes between the pair of rotary members 12 and 13 which form cuts *c*, to completely sever the tongues and remove the severed pieces *d*. The sheet then passes between feed rolls 14, 15, and a chopper or cut off mechanism including coacting knives 16, 17. The cut off mechanism which I preferably employ and which is diagrammatically illustrated is that described more in detail and claimed in my prior Patent No. 1,359,076, issued November 16th, 1920. The end of the sheet passes between feed rolls 18, 19 before the cut off action takes place, so as to hold the sheet taut during the cut off action, and the severed strips B are delivered by the feed rolls 18, 19 to any suitable receiving mechanism, as for instance a pair of feed rolls 20, 21, the lower of which is provided with a conveyor belt 22. The severed pieces *d* may correspond in length to the slots or recesses *e* which are to be formed in the edge of the strip, and in that event the parts are so proportioned and timed that the successive transverse cuts *f* will be spaced a distance equal to the width of a strip, and each transverse cut will be along a line coinciding with the ends of the several slots of a corresponding row. If desired the parts may be so proportioned, designed and timed that the waste pieces *d* will each be of a length equal to twice the length of a slot in the finished strip, and in that event the cut off mechanism will operate to make a transverse cut *h* which intersects all of the slots of a row intermediate of the ends of said slots and then a transverse cut *i* which will pass through the body of the sheet intermediate of two successive rows of slots. This arrangement is shown in Fig. 10. With the arrangement shown in Fig. 10, in order to avoid making the strips as rights and lefts, the slot-forming mechanism is so positioned as to form half width slots at each edge of the sheet. With the arrangement as indicated in Fig. 9, it is immaterial whether half width slots be formed in opposite edges, or full width slots along one edge only.

I do not wish to be limited to any par-

ticular mechanism for forming the tongues in the sheet. The details of the coacting rotary members 10 and 11 form no portion of my invention, and I do not wish to be limited to the forming of the tongues by a single pair of rotary members acting to cut three sides of the slot, as so far as my present invention is concerned, each of the three sides of the slot might be cut by a different pair of coacting members and at successive steps in the progress of the sheet through the machine. The specific rotary members 10 and 11 which are illustrated are substantially the same as those illustrated in Patent No. 1,182,416, issued May 9th, 1916. The lower member 11 includes a disk portion 25 carrying on its periphery a pair of shear blocks 26 and 27. The upper member 10 has a body portion 28 carrying a pair of slitting blades 29 spaced to a distance equal to the width of the slot which is to be formed in the sheet and adapted to coact with the opposite side edges of the shear block 26. The upper member also carries a cross blade 30 adapted to cooperate with one end of the shear block 26 and between it and the adjacent shear block 27. The length of the shear blocks and of the slitting knives 28, 29, corresponds to the length of the desired slots, and the members may be provided with shear blocks and knives for forming any desired number of slots, depending upon the length of the slots and the diameter of the members. The shear blocks and blades may be secured in position in any desired manner, and the members may be mounted for rotary, as well as longitudinal adjustment on their respective shafts. These members, as previously indicated, merely constitute one of many means which might be employed for forming U-shaped cuts, and attached tongues in the body of the sheet.

The coacting members 12 and 13 form an important feature of my invention and serve to sever each tongue at its base and to remove from the sheet the severed pieces. The upper member 12 as shown particularly in Figs. 6 and 8, serves as a platen and presents a hardened steel surface against which the cutter or blade of the lower member 13 acts to cut the sheet. Preferably the hardened steel surface is formed on a separate block 32 which is inserted in a recess or groove in the body of the member 12, so that this may be removed and replaced by a new one whenever desired. The block or hardened plate may be held in position in any suitable manner, as for instance by screws 33. The lower member 13 as shown particularly in Figs. 6 and 7, has a longitudinally extending radial groove in its periphery which receives the knife 34. The latter is held in place by a pair of screws 35 extending through a flange por-

tion 36, and with their heads disposed in a recess below the main peripheral surface of the member. The knife may be radially adjusted both endwise and radially in its 5 groove and is easily removed when it requires sharpening. The cutting edge portion 37 of the knife is of a length equal to the width of the base of the tongue which is to be severed, although preferably the 10 body portion of the knife is of materially greater length so as to be more effectively held by the screws 35. The two members 12 and 13 may be given rotary adjustment so as to change the line on the hardened 15 surface with which the cutting edge of the knife 34 engages so as to distribute wear.

The tab removing mechanism includes a pin 38 projecting from the surface of the member 12, and adapted to enter a recess 20 in the member 13. This pin 38 is so positioned that it passes through the severed piece closely adjacent to the front edge of the latter immediately after this front edge has been severed by the knife 34. Thus the 25 tongue which is drawn along by being attached to its front end, has its front end forced on to the pin 38 immediately after the front end has been severed from the body of the sheet, and while the tongue or 30 severed piece is gripped between the surface of the members 12 and 13 directly in the rear of the knife 34.

I do not wish to be limited to the placing 35 of this pin at any particular distance in the rear of the knife 34, as this distance may vary by a rotary adjustment of one member in respect to the other to vary the engagement of the knife and the backing plate or hardened steel surface. The flange 40 36 is preferably provided with a slot 39 into which the pin may pass, if the pin be adjusted to a position close to the knife. If they are at a greater distance, as illustrated in Fig. 6 the pin may pass through the material into the recess in the rear of the flange 36.

As the sheet passes on beyond the members 12 and 13, the severed pieces will remain fixed on the pins 38 and will be positively removed from the sheet and carried away from the sheet on the surface of the member 12. Suitable stripper mechanism is provided for removing the severed pieces 50 from the pins 38. As shown, there is provided a transversely extending trough 40 and a series of pivoted stripper plates 41 held firmly against the surface of the member 12 by a coil spring 42 or in any other suitable manner, and each stripper plate 55 has a slot 43 of a width materially less than the width of the severed piece and only slightly wider than the diameter of the pins 38. Thus each pin may pass through the slot of its corresponding stripper plate, 60 while the severed pieces will follow the up-

per surface of the stripper plates and drop into the trough 40. Suitable mechanism may be provided for removing the pieces from the trough, such for instance as that illustrated in my Patent 1,462,138 issued 70 July 12, 1923. I have illustrated the member 12 above the sheet, and the member 13 below the sheet, although it will of course be obvious that the position of these two parts may be reversed. 75

It will be noted that in case it is desired to cut double length slots, as indicated in Fig. 10, it is not necessary to make any change in the construction or design of the rotary members 12 and 13. They act the 80 same irrespective of the length of the severed piece. Any variation in the width of the severed piece may be taken care of merely by inserting a different knife 34 with the appropriate length of cutting edge. 85 Variation in the length of the slot may be accomplished by a substitution of knives 39 and shear blocks 26 of the proper length. If the removed pieces be comparatively wide, it will be obvious that a plurality of 90 pins 38 may be used for each severed piece. I have illustrated the pins 38 as being carried by the backing or platen plates 32, although this is not essential. The members 12 and 13 are very simple in construction, 95 and the several parts which are liable to wear or breakage may be very easily removed and replaced by new ones. Substitute parts for the members 10 and 11 may be readily obtained, as these are preferably 100 of a form now in common use on other types of machines for forming similar shingle strips.

I have referred to the severed pieces as "waste" pieces, but it will be apparent that if they be wider, as is necessary for some forms of shingle strips, the severed pieces may be used as individual shingles. I have illustrated the cutting mechanism of the members 12 and 13 as a knife and a platen or backing plate, but a pair of shear blades or a blade and a shear block similar to the blade 30 and block 26 might be employed. 110

By means of my improved mechanism the sheet may be cut as shown in Fig. 10, 115 which is not possible if the chopper is used to sever the tongues at their attached ends.

In the accompanying drawings I have not illustrated all of the details of the parts for supporting, driving and adjusting the various members. Such parts may be substantially the same as are illustrated in my patent above referred to.

Having thus described my invention, what I claim as new and desire to secure by 125 Letters Patent is:—

1. A machine for cutting shingle strips, including means for forming transverse rows of longitudinally extending tongues in a longitudinally advancing sheet, and a pair 130

- of coacting rotary members having knives spaced apart lengthwise of the members and each of a length equal to the width of a tongue for severing the tongues at their bases.
2. A machine for cutting shingle strips, including means for forming transverse rows of tongues in a longitudinally advancing sheet, and a pair of coacting rotary members having knives spaced apart lengthwise of the members and each of a length equal to the width of a tongue for severing the tongues at their bases, one of said rotary members having means carried thereby for removing the severed pieces from the sheet.
3. A machine for cutting shingle strips, including means for forming transverse rows of longitudinally extending tongues in a longitudinally advancing sheet, and a pair of coacting rotary members for severing the tongues at their bases, one of said members having a hardened surface and the other having a series of spaced cutters in alignment lengthwise of the member and coacting with the other member, and each of a length equal to the width of the tongue.
4. A machine for cutting shingle strips from sheet material, including means for advancing the sheet longitudinally, means for forming transverse rows of longitudinally extending tongues in the sheet, and a pair of rotary members, one of said members having a series of spaced cutters each of a length equal to the width of a tongue for severing the tongues at their bases, and the other rotary member having means for engaging with and removing the severed pieces.
5. A machine for cutting shingle strips from sheet material, including means for advancing the sheet longitudinally, means for forming transverse rows of longitudinally extending tongues in the sheet, and a pair of rotary members, one of said members being disposed at one side of the sheet and having a cutter for severing the tongues at their bases, and the other rotary member being disposed on the opposite side of the sheet, and having means for engaging with and removing the severed pieces.
6. A machine for cutting shingle strips from sheet material, including means for advancing the sheet, means for forming transverse rows of longitudinally extending tongues in the sheet, and a pair of rotary members, one of said members having a series of spaced cutters each of a length equal to the width of a tongue acting against the other member to sever the tongues at their bases, and one of said members having a pin for acting against the other member to penetrate the severed part and carry it from the plane of the sheet.
7. A machine for cutting shingle strips from sheet material, including means for advancing the sheet, means for forming transverse rows of longitudinally extending tongues in the sheet, and a pair of rotary members one of said members having a series of spaced cutters each of a length equal to the width of a tongue acting against the other member to sever the tongues at their bases, and the other of said members having a pin for penetrating the severed piece in the rear of the base end to carry said piece from the plane of the sheet.
8. In combination, means for forming a series of U-shaped cuts in a sheet of material, and a pair of rotary members independent of said means and between which the sheet is caused to pass, one of said members having a hardened surface and a projecting pin, and the other rotary member having a cutter acting against said surface to sever the part within the U-shaped cut, and a recess adjacent to the cutter to receive the pin.
9. A machine for cutting shingle strips from a sheet of material, including means for continuously advancing the sheet longitudinally, means for forming transverse rows of longitudinally extending tongues in the sheet, a pair of coacting rotary members for severing the tongues at their bases, one of said members having projecting means for penetrating the severed tongues and causing them to follow the surface of said member, and a stripper for removing the severed pieces from said surface.
10. A machine for cutting shingle strips, including means for forming transverse rows of longitudinally extending tongues in a longitudinally advancing sheet, a pair of coacting rotary members having knives each of a length equal to the width of a tongue for severing the tongues at their bases to form apertures, and separate means for severing the sheet along lines intersecting said apertures.
11. A machine for cutting shingle strips, including means for forming transverse rows of tongues in a longitudinally advancing sheet, a pair of coacting rotary members having knives each of a length equal to the width of a tongue for severing the tongues at their bases, one of said rotary members having means carried thereby for removing the severed pieces from the sheet, and means for removing the severed pieces from said member after the latter has removed them from the sheet.
12. A machine of the class described, including means for feeding a sheet of material endwise, means for cutting lengthwise thereof a row of U-shaped slits to form tongues projecting longitudinally of the sheet in the plane thereof, a pair of rotary coacting members for forming a series of spaced cuts transversely of the sheet to sever said tongues at their base ends and remove the severed pieces to thereby form a

series of apertures, and separate cutting mechanism for severing the sheet into sections each having a plurality of said apertures opening as slots along one edge there-
5 of.

13. A machine of the class described, in-
cluding means for feeding a sheet of ma-
terial endwise, means for cutting lengthwise
thereof a row of U-shaped slits to form
10 tongues, a pair of rotary coacting members
for forming cuts to sever said tongues at
their base ends and thereby form a series of
apertures, and separate cutting mechanism
for severing the sheet into sections each
15 having a plurality of said apertures opening
as slots along one edge thereof.

14. A machine of the class described, in-
cluding means for feeding a sheet of ma-
terial endwise, means for cutting lengthwise
20 thereof a row of U-shaped slits to form
tongues intermediate of the side edges of
the sheet, a pair of rotary coacting members
for forming cuts transversely of the sheet

to sever said tongues at their base ends and
thereby form a series of apertures, one of 25
said rotary members having a radial pin in
the periphery thereof, and the other of said
rotary members having a blade, means for
forcing the severed strips onto said pin, and
means for removing them therefrom. 30

15. A machine of the class described, in-
cluding means for feeding a sheet of ma-
terial endwise, means for cutting lengthwise
thereof a row of U-shaped slits to form
tongues, a pair of rotary coacting members 35
for forming a series of cuts to sever said
tongues at their base ends and thereby form
a series of apertures, one of said rotary mem-
bers having a platen and a pin, and the other
having a knife acting against the platen 40
and a recess receiving the pin.

Signed at Camden in the county of Cam-
den and State of New Jersey this 28th day
of June A. D. 1922.

SAMUEL M. LANGSTON.
